ATOMIC IRRADIATOR HOUSING

Milton Packin, Livingston, and Bernard Seid, Cedar Grove, N.J., assignors to Radiation Machinery Corporation, a corporation of New Jersey

Filed Jan. 7, 1969, Ser. No. 15,236

Term of patent 14 years

Int. Cl. D24—99
U.S. Cl. D16—2

Fig. 1

Fig. 2

Fig. 3

FIG. 1 is a front perspective view of an atomic irradiator housing showing our new design;

FIG. 2 is an enlarged scale rear elevational view thereof; and

FIG. 3 is an enlarged top plan view thereof.

The dominant features of our design reside in the full line portion of the drawing.

We claim:

The ornamental design for an atomic irradiator housing, as shown and described.
